United States Patent Office

Des. 185,128
Patented May 12, 1959

185,128

FIREPLACE TONGS

Alvin M. Cahan, Newton, Mass.

Application February 20, 1958, Serial No. 49,724

Term of patent 14 years

(Cl. D81—24)

Fig. 1 is a top plan view of fireplace tongs embodying my new design;

Fig. 2 is a perspective view thereof;

Figs. 3 and 4 are front and side elevational views, respectively, of the fireplace tongs; and

Fig. 5 is a perspective view illustrating the fireplace tongs in an open position.

I claim:

The ornamental design for fireplace tongs, as shown.
